(57) **CLAIM**

The ornamental design for the lamp as shown and described.

DESCRIPTION

FIG. 1 is a perspective view of a lamp according to our design;

FIG. 2 is a front elevational view thereof;

FIG. 3 is a rear elevational view thereof;

FIG. 4 is a left elevational view thereof;

FIG. 5 is a right elevational view thereof;

FIG. 6 is a top plan view thereof;

FIG. 7 is a bottom plan view thereof;

FIG. 8 is a perspective view of the lamp in a first alternative configuration where a shade of the lamp has been tilted to a first position relative to other elements of the lamp;

FIG. 9 is a perspective view of the lamp in a second alternative configuration where the shade of the lamp has been tilted to a second position relative to other elements of the lamp; and,

FIG. 10 is a perspective view of the lamp in a third alternative configuration where the shade of the lamp has been removed altogether.

1 Claim, 10 Drawing Sheets
